UNITED STATES PATENT OFFICE

THOMAS F. REID, OF BOISE, IDAHO

CARPENTER'S CLAMP

Application filed November 10, 1931. Serial No. 574,189.

This invention is a novel improvement in clamps for use by carpenters, cabinet makers, and the like; and the principal object of the invention is to provide a novel clamp particularly adapted to hold strips or boards and the like together, while drying, after they have been glued; the invention embodying a novel supporting beam mounted horizontally on supporting legs which are adjustable longitudinally relative to the beam, the invention further including novel quickly attachable and detachable clamping means for securing the supporting legs in adjusted position relative to the beam.

Most carpenter's clamps now in use are roughly cast and have unnecessary projections above and below the beams rendering same unwieldy to handle, and because of the projections the clamps cannot be stacked without some projection damaging the material below it. The principal features of my novel clamp are briefly an I-beam with flat surfaced top and bottom flanges, and heads adjustably mounted on the uppermost flange of the I-beam in such manner that no portion of the heads project below the bottom flange of the beam; also novel sets of legs which clamp effectively over the lowermost flange of the I-beam, whereby the I-beam itself may be turned over and the legs similarly clamped over the flange which carries the heads, and when the I-beam is so reversed a flat smooth surface is provided on the upper face of the I-beam which can be used very successfully as a support for a portable work bench.

A further object is to provide novel clamping legs which can easily and positively be attached and braced, and when not in use, or for purposes of transportation, may be conveniently folded up.

A still further object of the invention is to provide an all-metal clamp of the character above described, which will be simple in construction, strong, durable, efficient and reliable in use, and which may be manufactured at low cost.

I will explain the invention with reference to the accompanying drawing which illustrates one practical embodiment thereof, to

enable others to adopt and use the same; and will summarize in the claims the novel features of construction, and novel combinations of parts, for which protection is desired.

In said drawing:—

Fig. 1 is a side elevation of the clamp showing one of the legs supporting one end of the beam; also the heads on the beam holding the work therebetween, the work being shown in dotted lines;

Fig. 2 is a top plan view of the clamp shown in Fig. 1, partly broken away;

Fig. 3 is a section on the line 3—3, Fig. 1, showing in dotted lines the clamp legs in partly folded position for disengagement from the I-beam;

Fig. 4 is an enlarged section on the line 4—4, Fig. 1, showing the cam means for clamping the bracing block to the I-beam, and also showing in dotted lines the clamp releasing member swung into position to release the block;

Fig. 5 is a section on the line 5—5, Fig. 1; and

Fig. 6 is a section on the line 6—6, Fig. 1.

As shown in the drawing, my novel clamp preferably comprises an I-beam 1 of suitable dimensions for the purpose intended, the upperside of the lower flange of the I-beam being provided, at opposite sides of the web, with spaced opposed notches or recesses 2 adapted to receive and hold the toothed or pointed rear end of the clamping head 6, as shown in Fig. 1.

The head 6 (Fig. 6) comprises a casting having a flat front face 15, the casting being adapted to slide or rest upon the top of I-beam 1 and having jaws 6^a at its front side edges adapted to underlie the upper flange of the I-beam and prevent the head 6 from tipping off of the beam while permitting same to be moved longitudinally thereof. The rear ends of the lower side edges of the casting 6 are directed downwardly and inwardly and terminate as teeth 14 adapted to engage the notches 2 in the upper face of the lower flange of the I-beam, the parts being so shaped that when the teeth 14 are engaged with their notches the front face 15 of the casting 6 will be disposed at right angles to the top face of

100

the I-beam. Extending down through the casting 6 is a bore 6^b at the lower end of which is a pin 17 adapted to rest upon the top of the I-beam 1. In bore 6^b above the 5 pin 17 is a spring 16 retained in the bore by means of a plug 16^a, screwed or otherwise secured into the top of the bore 6^b. The spring 16 acting upon the pin 17 normally tends to hold the front end of the head 6 slightly 10 raised so as to maintain the teeth 14 engaged with the notches 2. When however, it is desired to change the position of the head 6, the front end of the casting 6 may be pushed downwardly towards the I-beam, which 15 movement will rock the head on the I-beam sufficiently to disengage the teeth 14 from the notches 2, whereby the head can be moved or shifted axially of the I-beam into desired position. On releasing the downward pressure 20 on the head the spring 16 will again tilt the head so as to maintain the teeth 14 in engagement with the intended notches 2.

The adjustable head 5 comprises a casting having a flat bearing face, the casting being 25 adapted to rest upon the upper flange of the I-beam 1, said casting having jaws 5^a (Fig. 5) shaped to underlie the upper flange of the I-beam to prevent the head from tipping off the beam while permitting same to slide along 30 the top flange thereof. At the adjacent end of the I-beam is a tapered bearing 4, securely riveted or otherwise secured to the beam, through which bearing extends a screw shaft 3 having a handle 10 on its outer end for rotating the shaft. The inner end of screw shaft 3 is reduced in diameter as at 3^a and enters a bore 5^b in the rear end of head 5, and a ball thrust bearing, denoted by the reference characters 8 and 9, is interposed between the 35 head 5 and threaded portion 3 of the shaft to facilitate clamping with less physical exertion. A set screw 7 engaging an annular groove 3^b in the reduced portion 3^a of shaft 3 prevents separation of the head and shaft 40 while permitting rotation of the shaft with respect to the head, whereby the head 5 may be moved axially along the I-beam.

The I-beam 1 is supported upon pairs of legs hinged together to form A-frames, the 45 legs at only one end of the beam being shown in the drawing, but it is understood that the legs at the other end of the beam would be similar. Each pair of legs comprises opposed channel-bars 18 of suitable proportions having 50 inturned portions 19 at their upper ends adapted to form a horizontal support for the I-beam 1, the portions 19 being connected together by a hinge 22 underlying the portions, whereby the opposed legs 18 may be swung 55 towards or away from each other. Immediately below the flattened portions 19 the legs 18 diverge downwardly and outwardly as shown in Fig. 3 and the lower ends of the legs are flattened and outturned, as at 19^a to engage 60 the ground or floor surface G. The piv-

otating movement of legs 18 is controlled by a hinge strap 23 having its ends engaging hooks 25 mounted upon the legs to prevent the legs from spreading too far apart, and to give required rigidity to the legs, one of the hooks 25 being threaded for receiving a wing nut 25^a engaging the outer face of the channel leg. A small nut 24 is located on the hook 25 adapted to engage the inner face of the channel leg 18 to regulate the spread of the legs.

Upon the inturned portions 19 of legs 18, at opposite sides of the I-beam, are grippers 20 adapted to fit securely over the lower flange of the beam and to maintain the I-beam locked upon the legs when the legs are separated, as shown in full lines in Fig. 3. The grippers preferably comprise plates 20 shaped to conform with the curvature of the legs and are securely riveted thereto, said plates carrying at their inner ends offset flanges 20^a adapted to fit over the tops of the lower flanges of the I-beam 1 when the legs 18 are spread apart as in full lines in Fig. 3, and the spread of the legs regulates the bite of the grippers 20 upon the flange of the I-beam since the further apart the legs are forced the tighter the grippers 20 will bite the flange of the I-beam. When it is desired to remove the legs 18 from the I-beam it is merely necessary to push the members 23 downwardly adjacent their common pivot point so that the members 23 will be shifted from the axially aligned position shown in full lines Fig. 3 into the angularly disposed position shown in Fig. 3 so as to swing the legs together, whereby the gripper flanges 20^a on the legs will be separated sufficiently to permit removal of the I-beam from between the flanges 20^a. The gripper plates 20 preferably extend the full width of each leg 18 and are long enough to reach around the upper bends of the leg to reinforce same. The inner ends 23^a of the strap sections 23, beyond the common pivot point, are provided with lugs 23^a (Fig. 3) adapted to underlie the adjacent section 23 when the sections are aligned as in full lines, Fig. 3, to limit the movement of the sections when swinging same into alignment.

I also provide leg braces 26, with novel means for adjustably fastening the same to the I-beam. One end of each brace 26 is preferably disconnectably connected to its respective leg 18, and the other end to a brace block 27, the blocks 27 being disposed at opposite sides of the I-beam as shown in Figs. 1 and 4, and having inturned upper ends 27^a adapted to overlie the lower flange of the I-beam. The blocks 27 extend below the lower edge of the I-beam, and through the depending portions of the plates extends a U-bolt 28, upon the base of which is pivoted a handle 29 having cam head 29^a adapted to engage the adjacent block 27. The legs of the U-bolt pass through the opposite block 27 and are pro-

vided on their ends with nuts as shown. Interposed between the blocks 27 below the I-beam is a coil or other spring 30 normally tending to separate the blocks 27 whereby when the handle 29 is swung upwardly into substantially horizontal position, as shown in dotted lines in Fig. 4, the spring 30 will separate the blocks 27 sufficiently to permit the flange of the I-beam to be withdrawn from between the flanges 27^a, or to permit the blocks 27 to be adjusted axially of the I-beam. When however handle 29 is swung downwardly, as shown in full lines in Fig. 4, the cam 29^a will draw the blocks 27 together and frictionally lock the blocks in adjusted position on the I-beam, whereby the links 26 will effectively brace the legs 18.

The I-beam 1 and the supporting legs 18 with their braces 26 may be quickly assembled and adjusted with respect to each other as hereinbefore described, or the legs 18 and braces may be quickly removed by manipulating the handle 29 and hinging the legs 18. The work W may be held securely clamped between the heads 5 and 6 resting upon the top of the I-beam, thereby leaving no protections or parts extending below the bottom of the I-beam, whereby the I-beams carrying the heads and work may be readily stacked one upon the other without injury to the work. If desired, the I-beams with heads 5 and 6 may be turned over and the legs 18 and braces secured to the same beam flange as the heads forming a convenient portable work bench support having a flat upper surface with no projections. When not in use the pairs of legs 18 may be readily folded up, or packed for transportation. The entire clamp is made of metal and the parts securely riveted or bolted together, and all parts of the heads are machined with true faces and edges.

I claim:

1. In a support for I-beams having upper and lower flanges; a leg frame comprising a pair of opposed legs hinged together at their upper ends to form a substantial A-frame; means connecting the legs below the hinge for limiting the spread of the legs; and grippers on the legs at opposite sides of the hinge adapted to fit over the lower flange of the beam when the legs are swung apart, said grippers separating to release the flange when the legs are swung together.

2. In combination with a support as set forth in claim 1, a removable clamp adapted to engage the I-beam, and brace rods connecting the clamp plate and frame.

3. In combination with a support as set forth in claim 1, opposed clamp plates adjacent the leg frame adapted to engage opposite sides of the flange, brace rods connecting the clamp plates and frame; and means for expanding and contracting the clamp plates with respect to the flange.

4. In a support for I-beams having upper and lower flanges; a leg frame comprising a pair of opposed legs hinged together at their upper ends to form a substantial A-frame; a strap having hinged sections connecting the legs below the hinge for limiting the spread of the legs; means for adjusting the degree of spread of the legs; and grippers on the legs at opposite sides of the hinge adapted to fit over the lower flange of the beam when the legs are swung apart, said grippers separating to release the flange when the legs are swung together.

5. In combination with a support as set forth in claim 4, a removable clamp adapted to engage the I-beams, and brace rods connecting the clamp and frame.

6. In combination with a support as set forth in claim 4, opposed clamp plates adjacent the leg frame adapted to engage opposite sides of the flange, brace rods connecting the clamp plates and frame; and means for expanding and contracting the clamp plates with respect to the flange.

7. In a support for I-beams having upper and lower flanges, a leg frame comprising a pair of opposed legs hinged together at their upper ends to form a substantial A-frame; means connecting the legs below the hinge for limiting the spread of the legs; and grippers on the legs at opposite sides of the hinge adapted to fit over the lower flange of the beam when the legs are swung apart, said grippers separating to release the flange when the legs are swung together; said legs comprising channel bars having their upper ends inturned adjacent the hinge, the flanges of the channels being flattened through the turned portions adjacent the grippers.

8. In combination with a support as set forth in claim 7, a removable clamp adapted to engage the I-beam, and brace rods connecting the clamp and frame.

9. In combination with a support as set forth in claim 7, opposed clamp plates adjacent the leg frame adapted to engage opposite sides of the flange, brace rods connecting the clamp plates and frame; and means for expanding and contracting the clamp plates with respect to the flange.

10. In a support for I-beams and the like having a flange, a leg frame removably connected to the beam; opposed clamp plates adjacent the leg frame at opposite sides of the flange; brace rods connecting the clamp plates and frame; a spring between the plates for normally urging the plates to separate; and cam means for drawing the plates together.

11. In a support for I-beams and the like having a flange, a leg frame removably connected to the beam; opposed clamp plates adjacent the leg frame at opposite sides of the flange; brace rods connecting the clamp plates and frame; a U-bolt; said clamp plates

- being slidably mounted on the U-bolt; and a cam rotatably mounted on the base of the U-bolt adapted to draw the plates together when rotated into one position.
- 5 12. In a support for I-beams and the like having a flange, a leg frame removably connected to the beam; opposed clamp plates adjacent the leg frame at opposite sides of the flange; brace rods connecting the clamp
- 10 plates and frame; a U-bolt; said clamp plates being slidably mounted on the U-bolt; a spring between the plates for normally urging the plates to separate; and a cam rotatably mounted on the base of the U-bolt
- 15 adapted to draw the plates together when rotated into one position.
